UNITED STATES PATENT OFFICE.

AUSTIN N. OPPENHEIM, OF BALTIMORE, MARYLAND.

ATHLETIC UNION GARMENT.

Application filed December 1, 1922. Serial No. 604,148.

To all whom it may concern:

Be it known that AUSTIN N. OPPENHEIM, a citizen of the United States, residing at Baltimore, in the State of Maryland, has invented certain new and useful Improvements in Athletic Union Garments, of which the following is a specification.

This invention relates to improvements in athletic union garments and has for its object to provide an improved construction of union garment of the woven fabric type wherein the crotch is closed; both the front and back are free of vertical plackets from the neck down to the waist; the front and rear are permanently connected across one shoulder between one arm-hole and the neck-opening while across the other shoulder there is provided a strap which extends from the rear body-part and laps over onto the front body-part and is detachably connected to said latter body-part.

According to my invention, the athletic garment will be free of the front placket from the neck to the crotch and will therefore also be free of buttons down the front which buttons frequently become detached leaving the front placket gaping.

By therefore providing an athletic under-garment of the usual woven fabric with but one detachable fastening that must be manipulated to put the garment on or take it off, I produce a garment that is much simplified, very comfortable and which will avoid the annoyance to a wearer who when he puts an open front garment on finds one or more buttons missing from the front placket.

The invention is illustrated in the accompanying drawing, wherein:-

Fig. 1 shows the improved garment in perspective as viewed from the front, and

Fig. 2 illustrates, on an enlarged scale, the upper portion of the garment to bring out more clearly the connections between the front and rear body-parts which connections separate the neck-opening from the arm-hole openings.

Fig. 3 is a section on the line 3—3 of Fig. 2.

By reference to the drawing it will be noted that the garment which is made principally of woven fabric has a front 3 comprising an upper body-part 4, and a lower leg-part 5, and that said body-part is permanently closed at the front from the neck-

opening 6, down, in that no front placket is employed.

At the crotch 7, the garment is permanently closed by any suitable crotch structure, such for example as by crotch insert strips 8, which are permanently stitched in the legs and extend across the crotch in the usual manner.

A slit 9, see broken lines in Fig. 1, is provided in the front of the garment above the crotch, for obvious purposes, and this slit is covered by a short flap 10, that is permanently stitched to the garment front, but has one vertical edge 11, thereof free so the same may be turned back.

In the present instance the rear of the garment has an upper back-part 12, and a cross-wise insert 13, of the usual elastic webbing is provided in the back at about the waist-line. A posterior flap 14, is also provided at the rear of the garment as indicated by broken lines in Fig. 1.

The neck-opening 6, as is usual in athletic underwear, extends well down or is cut low at the front of the garment to provide ample opening about the neck.

Arm-holes 15, of ample size are also provided as is usual in this class of athletic garments.

At the right shoulder there is provided an elastic strap connection 16 which has its rear end permanently connected to the upper edge of the rear body-part 12 while its front end is permanently connected to the front body-part 4. This elastic connection 16 therefore provides a fixed and permanent elastic connection between the front and back, both of which are woven material and therefore are inelastic, and this strap 16 also permanently separates the neck-opening 6 from the right arm-hole 15.

At the opposite or left shoulder of the garment there is provided an elastic connection or strap 17 whose rear edge 18 is permanently stitched to the upper edge of the rear body-part 12 and whose front edge 19 overlaps the upper edge of the front body-part 4 of the garment and is detachably connected to said front body-part by fastenings 20.

The elastic connection strip 17 forming the left shoulder of the garment is formed of webbing of woven material. This strip of webbing is folded so that at each of its longitudinal sides the fold will form a fin-

ished edge and by thus folding the webbing along the two sides it produces a double-thickness that reinforces the strap.

The front detachable edge 19 of the connection strap 17 is provided on its under side with a strip 21 to the elastic strap 17, shown in broken lines in Fig. 2, which strip is of inelastic material, and the attachment of this strip 21 renders the front edge of the strip 17 inelastic at the point where the detachable fastenings 20 engage the same but leaves the rear portion of the strip 17 free to stretch longitudinally.

It will thus be noted that the only fastening to retain the garment on the body is the connection strap 17 on the left shoulder and this connection fastens at its forward edge to the upper edge of the front body-part.

It will further be noted that when the elastic connection 17 is detached at 20, the neck-opening 6 and the large left arm-opening 15 will together form an opening of sufficient size to enable the garment to be drawn up over the legs and body of the wearer and that when drawn up, the one connection 17 on the left shoulder may readily be fastened with the fingers of the right hand of the wearer and the garment thus be held in place on the body.

The manner of construction the detachable strip 17, made as it is, through a combination of elastic and inelastic material, is designed to give just the right amount of

yielding and elasticity at the shoulder necessary for comfort and at the same time, to insure enough strength and resistance against the buttoning and unbuttoning process whenever the garment is put on or off,— the wear and tear being principally on the 40 detachable strip.

By providing the strip 21 of inelastic material on the under side of the connection 17 the latter is rendered inelastic at the fastenings and danger of tearing at those fastening is minimized.

Having described my invention, I claim,—

A one-piece undergarment of inelastic material, comprising a unitary body and leg portion having relatively large arm openings and a neck opening between them, a separable shoulder strap separating the neck opening from one arm opening and adapted when disengaged to provide a slip-on as the combined neck opening and one arm opening are of a size to freely admit the body to the garment, said separable shoulder strap of elastic woven material and having a pair of buttonholes in said elastic material, a pair of buttons on the front portion of the garment to enter the buttonholes, and a strip of inelastic material secured beneath the end of the strap and having registering buttonholes and preventing stretching of the strap at the buttonhole end.

In testimony whereof I affix my signature.

AUSTIN N. OPPENHEIM.
